2,558,403

PNEUMATIC TACKER

Oscar A. Wandel, Chicago, Ill., assignor to
Henry A. Törstenson, Chicago, Ill.

Application January 3, 1948, Serial No. 421

4 Claims. (Cl. 1—49)

1

This invention is concerned with improvements in a portable tacker or fastener driving device which is adapted to drive a U-shaped staple into a surface of wood, cardboard or similar material. More particularly, the invention is concerned with a fastener driving device of the type which comprises a forward chamber having a vertical fastener guideway therein, a reciprocal driving plunger in the driveway, a bottom horizontally disposed fastener feeding chamber provided with means for delivering fasteners to driving position beneath the plunger and a mechanism for operating the plunger.

It is an object of the invention to provide in a fastener driving device of the type described a pneumatically actuated plunger operating means.

A further object of the invention is to provide a fastener driving device of the type described in which the plunger operating mechanism comprises a driving spring and a pneumatically operating trip mechanism for compressing the spring and then releasing it to operate the plunger.

Another object of the invention is to provide a fastener driving device of the type described wherein a pneumatic unit is provided which can be readily substituted for the conventional pivoted handle member for cooperation with the trip mechanism to operate the driving plunger.

These and other objects of the invention will be apparent from a consideration of the preferred form of the device which is shown by way of illustration in the accompanying drawings, wherein:

Fig. 1 is a perspective view of a fastener driving device having incorporated therein a pneumatic unit which illustrates the principles of the invention;

Fig. 2 is a side elevation of the device to an enlarged scale with portions thereof broken away; and

Fig. 3 is a section on the line 3—3 of Fig. 2.

The present invention is applicable to various kinds of fastener driving devices such as stapling machines, compression tackers, magazine hammers, etc. which include a plunger operating mechanism having a trip means.

For convenience in illustration the invention is shown embodied in a tacker used for driving U-shaped staples.

A handle operated tacker of this type is shown and described in the copending applications of Kenneth D. Morberg, Serial No. 629,675, filed November 5, 1945 and issued as U. S. Letters Patent No. 2,548,736, on April 10, 1951; Serial No. 717,-

2

692, filed December 21, 1946 and issued as U. S. Letters Patent No. 2,456,526, on December 14, 1948; and Oscar A. Wandel, Serial No. 778,953, filed October 9, 1947, and issued as U. S. Letters Patent No. 2,556,992 on June 12, 1951, to which reference is made for detailed description of those features which are not described in detail in this application.

The illustrated form of the tacker comprises a generally U-shaped frame 10 having a forward chamber or driving head 11 formed by spaced vertical frame side plates 12 and 13, the forward ends of which are turned inwardly to provide flanges 14 and 15 defining part of the front face of the tacker and the forward side of the guideway for the driving plunger 16 which is mounted for vertical reciprocation therein.

The driving plunger 16 is mounted for reciprocal movement on a fixed guide post 17 and is actuated by a compression spring 18 which surrounds the post 17 with its lower end seated in a recess 19 in the upper end of the plunger 16. The spring 18 extends to cap 20 at the top of the guideway. The plunger 16 carries a staple driving blade 21 at the bottom end of the forward face thereof. The driving plunger 16 is adapted to be elevated and then released for the driving stroke by a trip mechanism 22 within the driving head 11.

The tacker is provided with a staple supply magazine which is arranged in a horizontally extending chamber in the bottom portion 23 of the outer frame 10 and which delivers staples or fasteners to driving position beneath the driving blade 21 at the forward end of the tacker, the forward portion of the guideway for the fasteners being formed by a generally U-shaped front plate member 24 which is secured on the frame 10 by the transverse pin 25.

The trip mechanism 22 is actuated by a piston rod 26 which is connected by the link 27 with the top end of the bell crank member 28 which forms part of the trip mechanism 22 and which is pivoted about the transverse pin 29 which is removably mounted in the spaced side plates 12 and 13.

The piston rod 26 is mounted for horizontal reciprocation in a generally tubular casing 30. The rod 26 slides in bearing forming plug assemblies 31 and 32 which are secured in the forward and rearward end of the casing 30. The plug assembly 31 is provided with a sleeve 33 for receiving the forward end of the piston rod 26. The plug assembly 32 is provided with a sleeve 34 for re-

ceiving the reduced rearward end of the piston rod 26.

The rod 26 carries a piston assembly 35 which is urged in the forward direction by a compression spring 36. Compressed air is admitted to the chamber 31 formed between the plug assemblies 31 and 32 in the housing 30 through a passageway 38 extending downwardly into the handle or grip member 39 and connected by a valve 40 and passageway 41 with a hose coupling 42 for receiving a compressed air supply line.

The valve 40 is reciprocably movable in a horizontal direction and is operated by a trigger 43 secured at the forward end of the handle forming portion 39. A pressure release vent or aperture 44 is provided for permitting the air to escape and allowing the piston 35 to be returned by the spring 36 when the valve 40 is closed. The handle forming portion 39 is secured between the upright frame members 45 and 46 of the frame 10 and is preferably formed of a material having indentations along the lower edge for accommodating the fingers of the user.

The casing 30 has a forward portion 47 which extends approximately to the cap member 20 in protecting relation to the trip mechanism member 28 and the connecting link 27. The casing 30 and the handle forming portion 39 are constructed so that the pneumatic mechanism and the trip mechanism 22 may be readily removed as a unit by removing the mounting pins 48 which secure the handle forming portion 39 between the frame members 45 and 46 and the pivot pin 29. The pins 48 and 29 on which the trip mechanism 22 is mounted may be removably secured in the side frame plates 12 and 13 in any conventional manner.

In using the tacker the trip mechanism is actuated by the piston rod 26 which is controlled by the trigger operated valve 40. The driving plunger 16 is raised and released for the driving operation by operation of the trip mechanism 22.

The pneumatic operating unit is readily substituted for the handle heretofore used in this type of tacker and thus provides a light, compact, easily attached unit for converting the tacker from hand operation to pneumatic operation. With the arrangement of cooperating trip mechanism and pneumatic actuator there is no kickback on the tacker due to the pneumatic mechanism when the driving operation is performed. The pneumatic mechanism merely releases the driving plunger for the driving operation through actuation of the compression spring 18 and the trip mechanism 22.

While specific details of materials and construction have been referred to in describing the preferred form of the invention, it will be understood that other materials and other details of construction may be resorted to within the spirit of the invention.

I claim:

1. In a fastener driving mechanism having a housing, a spring actuated driver mounted in a guideway in the housing and fastener feeding means for delivering fasteners in driving position, the improvement comprising a trip mechanism for raising the driver against the action of the spring to a predetermined position and then releasing the same and a pneumatic means for actuating the trip mechanism comprising a

reciprocable rod and a link connecting the end of said rod with said trip mechanism.

2. A fastener driving mechanism comprising a housing having a guideway, a driver mounted in said guideway, means for delivering fasteners to a driving position relative to the driver, a compression spring for actuating the driver, a trip mechanism for moving the driver against the action of the spring to a predetermined position and then releasing the same to drive a fastener, means for removably mounting said trip mechanism in said housing, a pneumatic unit having a reciprocable rod for actuating the trip mechanism, means for removably mounting said pneumatic unit on said housing, and an operating member pivotally connecting said trip mechanism and said reciprocable rod.

3. In a fastener driving mechanism having a frame, a guideway in a forward portion of the frame, a spring actuated driver mounted in the guideway and fastener feeding means for delivering fasteners in driving position beneath the driver, the improvement comprising a trip mechanism for raising the driver against the action of the spring to a predetermined position and then releasing the same, said trip mechanism including a pivotally mounted operating lever separably mounted on said frame, pneumatic means for actuating the trip mechanism, said pneumatic means including a reciprocable rod and a housing therefor, means for separably mounting said housing on said frame with the end of said rod adjacent said operating lever, and a connecting link between the end of said rod and said trip mechanism operating lever.

4. In a fastener driving mechanism having a frame member of upwardly opening U-shaped form, characterized by a chamber forming head portion and laterally spaced handle grip portions extending rearwardly of said head portion, a spring actuated driver mounted in a guideway in said chamber, fastener feeding means for delivering fasteners in driving position beneath said driver, a trip mechanism in said chamber for raising the driver against the action of the spring to a predetermined position and then releasing the same, said trip mechanism comprising a bell crank member swingably mounted on a removable pin, pneumatic means for actuating said trip mechanism, means for detachably mounting said pneumatic means between said handle grip portions, said pneumatic means having a reciprocable rod extending toward said trip mechanism, and a member pivotally connected with said bell crank and said reciprocable rod whereby upon reciprocal movement of said rod said bell crank is swung about its pivotal mounting.

OSCAR A. WANDEL.
